UNITED STATES PATENT OFFICE

169,229

AMUSEMENT RIDE CAR

Allan H. Tober, Snyder, N. Y., assignor to Allan Herschell Co., Inc., North Tonawanda, N. Y.

Application October 4, 1952, Serial No. 21,689

Term of patent 14 years

(Cl. D34—15)

To all whom it may concern:

Be it known that I, Allan H. Tober, a citizen of the United States, residing at 25 Northledge Drive, Snyder, New York, have invented a new, original, and ornamental Design for an Amusement Ride Car, of which the following is a specification, reference being had to the accompanying drawing, forming part thereof.

In the drawing:

Fig. 1 is a front perspective view of an amusement ride car, showing my new design;

Fig. 2 is a rear perspective view thereof; and

Fig. 3 is a top plan view thereof, to an enlarged scale.

I claim:

The ornamental design for an amusement ride car, as shown.

ALLAN H. TOBER.
